UNITED STATES PATENT OFFICE.

EDWARD D. McKENNA, OF BROOKLYN, NEW YORK.

HOLDER FOR SALES-CHECKS.

No. 828,044.

Specification of Letters Patent.

Patented Aug. 7, 1906.

Application filed February 10, 1906. Serial No. 300,390.

To all whom it may concern:

Be it known that I, EDWARD D. McKENNA, a citizen of the United States, residing at 209 Nassau street, Brooklyn, in the county of 5 Kings and State of New York, have invented certain new and useful Improvements in Holders for Sales-Checks, of which the following is a specification.

The invention to be hereinafter described 10 relates to holders for sales-checks, and has for its object the provision of a simple, durable, and convenient form of such devices whereby the sales-checks may be conveniently and securely retained in the holder 15 and yet the stubs thereof may be readily and speedily replaced by a new set of sales-checks without the necessity of special unlocking devices.

In some of the prior devices for holding 20 sales-checks it was generally considered necessary to so devise the construction that no check or stub could be removed from the holder without a special unlocking device, such as a key, for instance. This, however, 25 led to much trouble in the rush of business when a replenishment of checks became necessary. In such case the waiter in a restaurant using such special devices was compelled to go to a particular place and a particular 30 person to secure the unlocking-key before he could take out the old stubs and replenish the sales-checks. In the present invention, however, these objectionable delays are overcome by providing on the exterior of the 35 hinged cover of the holder a locking device or catch which can be moved by the thumb or finger to speedily and readily disengage it from the sales-check-retaining means, so that the person using the holder can conveniently 40 take out the old stubs and put in a new supply of checks at the replenishing-station, any loss being prevented by the fact that the checks are numbered consecutively and both the stub and coupon bear such number and another number corresponding to 45 the waiter's number on the holder.

The invention therefore consists of the parts and combinations, as hereinafter more fully described, and definitely pointed out in 50 the claims.

In the drawings, Figure 1 is a perspective view of a holder for sales-checks embodying the present invention. Fig. 2 is a like view with part of the coupons torn off, leaving the 55 stubs showing the hinged cover unlocked and turned down so that said stubs can be re-

moved from the holder. Fig. 3 is a front view of the holder shown in Fig. 1 and illustrates the locking device in locked position on the front or exterior face of the cover. 60 Fig. 4 is a view similar to Fig. 3 with the locking device in unlocked position. Fig. 5 is a central sectional view of the holder with the sales-checks removed and showing the hinged cover in its lowered position. Fig. 6 65 is a perspective view similar to Fig. 1 of another form of the invention. Fig. 7 is a central longitudinal section of such other form of holder. Fig. 8 is a front elevation of the holder shown in Fig. 6, illustrating more particularly the locking device or catch; and Fig. 9 is a view similar to Fig. 8 with the hinged cover turned downward.

The holder of the present invention comprises a box-like frame, (designated as a whole 75 by the letter A, Figs. 1 and 2.) This box-like frame consists of side and bottom pieces suitably joined together and has an open side *a*, Fig. 5, and likewise an open end *b*, Fig. 5. To this extent there is nothing of peculiar 80 novelty in the holder. On the interior of the holder A are the retaining means *c* for the sales-checks. Such retaining means in the form shown by Figs. 1 to 5, inclusive, consist of beads or rods extending longitudinally 85 of the holder on the interior thereof, as shown in Fig. 5, and said retaining means, as shown in Fig. 2, are adapted to engage suitable recesses *c'* on the edges of the stub portions of the sales-checks, (see Fig. 2,) whereby the 90 sales-checks and their stubs are prevented from being removed upwardly from the holder, as shown in Fig. 2. The character of sales-checks used in this form of device comprise a stub *d* and a coupon *d'*, supported by 95 a line of perforations *d*², whereby the coupon portion may be readily torn from the stub portion in the usual transaction of business, as will be well understood. In order that these stub portions may be readily removed 100 from the holder after the sales-checks or coupon portions thereof have been completely used up, there is pivotally mounted on or hinged to the box-like frame A, adjacent the open end *b* thereof, a cover *e*, as 105 shown in Figs. 1, 2, and 5. This cover *e* may be hinged to the box-like frame A in any suitable manner; but in the present form of the invention, as shown in the figures referred to, the cover is provided with ears *e'*, which embrace the box-like frame, and a rod *e*³ passes 110 transversely of the frame through the ends of

such ears. At the other portion of the cover near the top thereof there are also embracing ears e^2 .

The cover e at each side thereof is provided with suitable recesses e^4 , through which pass the projecting ends of the retaining means c , Fig. 2, such retaining means being provided with a groove c^3 for engagement with locking edge f of a catch or lock F .

10 The catch or lock F is mounted upon the exterior surface of the cover e and is adapted to be turned to bring the locking edge f into engagement with the recesses c^3 in the retaining means, as will be clearly understood from Figs. 3, 4, and 5, a handpiece or knob f' being provided for turning the locking device or catch F upon the face of the cover e .

From the construction described it will be noted that when the cover e is turned into its 20 closing position the ears e^2 at the upper portion thereof will embrace the upper edge of the box-like frame, and thereby position the cover, and then by simply turning the locking device or catch F by means of its knob f' 25 the locking edges f thereof are brought into engagement with the single notch or recess c^3 on the retaining means at each side of the box-like frame.

Sustained in an upright position within 30 the box-like frame is a follower G , having secured thereto near its upper portion a spring g , the lower end of which extends within the box-like frame and bears upon the rear wall b' thereof, whereby the sales-checks placed 35 within the holder are maintained in substantially rigid position and normally pressed forward or toward the cover e . The follower G , like the stub portions d of the sales-checks, is guided on the retaining means c on the interior of the box-like frame.

40 Any suitable means may be provided, as the strap G' , on the side of the frame for holding the entire structure and its contents upon the person by means of the strap or other means, as will be well understood.

From the construction described it will be noted that the holder is adapted to receive and hold sales-checks and that these sales-checks may have any suitable inscription on 50 the face thereof—as, for instance, the checks may be numbered consecutively on the stub and the coupon portions thereof bear such number as well as the number of the waiter who carries the holder. When a series of 55 coupons have been used and it is desirable to replenish the holder with a series of sales-checks, it is only necessary for the waiter to turn the knob f' of the locking device or catch F , whereupon the cover e may be turned 60 downward, as shown in Fig. 2, and the stubs of the used coupons can then be readily removed, the follower G at such time remaining in its normal position though pressed forward by the spring g . The new set of sales-checks having been introduced and pressed

backward against the follower and spring g , the cover e is turned into its closing position and the locking device or catch F turned, by means of the knob f' , so that the locking edges f will engage the single recesses c^3 at the ends 70 of the retaining means c , which project beyond the side pieces of the holder and through the recesses e^4 at the side of the hinged cover.

In Figs. 6, 7, 8, and 9 a somewhat different form of holder and locking device or catch is 75 illustrated. Therein the holder comprises a box-like frame, as before, having secured to its rear wall 1 a single spindle 2, projecting centrally forward beyond the open end of the box-like frame, where the spindle is provided 80 with a single recess, as shown in Fig. 7, to be engaged by the locking device or catch, to be described.

Hinged to the box-like frame, Figs. 6 to 9, is the hinged cover 3, connected to the frame 85 by the hinge 4 and having pivotally mounted on the exterior face thereof the locking device or catch 5, pivoted at 6 and provided with a knob or handle 7. This locking device or catch 5, as shown in Fig. 8, has its 90 lowered end recessed at 8, so that its projecting end 9 will engage the side of the spindle 2 and enter the single recess at the end thereof in order to hold the cover in closed position. Sustained within the box-like frame is the 95 follower 10, having a central opening 11 for engaging the spindle 2, on which it may slide, said follower being urged normally forward by means of a spring 12, secured near its upper end and extending within the box-like 100 frame. A suitable means, such as the clip 13, pivoted at 14 upon the side of the box-like frame and provided with a thumb-piece 15 and a suitable spring or springs 16, may be provided for holding the device upon the 105 person of the waiter using the same. It will be noted that in this construction the hinged cover 3 is provided with side portions, as shown in Fig. 6, which embrace the outer edges of the box-like frame and serve to position the cover as it is moved to its closing 110 position, a suitable perforation, as 17, being provided in the cover for the accommodation of the spindle 2, which projects therethrough, as shown in Figs. 7 and 9. In this form of 115 the device, as in that previously described, it will be noted that the locking device consists of a swinging catch which is mounted upon the outer surface of the cover and has a handle or knob by which it can be readily moved 120 on its pivotal connection with the cover to carry its locking portion into engagement with or out of engagement from the notch in the retaining means for the sales-checks.

In each device the cover is readily locked 125 and unlocked, so that it can be closed or opened at will without the provision of a special key or other specially-devised means separate from the holder itself.

Having thus described my invention, what 130

I claim, and desire to secure by Letters Patent, is—

1. A holder for sales-checks comprising a box-like frame having an open side and end, retaining means secured to the interior of the frame for retaining the sales-checks therein, a flat spring for normally pressing the sales-checks toward the end of the frame, said spring engaging and being guided by the said retaining means, a cover for said end hinged to the box-like frame, a catch pivotally mounted on the exterior of said cover and having a portion to engage with the retaining means for the sales-checks to thereby hold said cover in closed position, said catch being provided with a handpiece or knob exterior of the cover for operating the catch.

2. In a holder for sales-checks, the combination of a box-like frame having an open end and side, retaining means for the sales-checks extending longitudinally of the frame at each side on the interior thereof, a hinged cover for closing the open end of the frame, a locking-catch rotatably mounted on the ex-

terior surface of the hinged cover and having a handpiece for operating it, said locking-catch having locking edges for engaging the retaining means extending on each side of the box-like frame.

3. In a holder for sales-checks, the combination of a box-like frame having an open end and side, retaining means for the sales-checks extending longitudinally of the frame at each side on the interior thereof, a hinged cover for closing the open end of the frame, and having recesses at each side thereof, a locking-catch rotatably mounted on the exterior surface of the hinged cover and having a handpiece for operating it, said locking-catch having locking edges for engaging the retaining means extending on each side of the box-like frame.

In testimony whereof I affix my signature in presence of two witnesses.

EDWARD D. McKENNA.
